CLAIM

The ornamental design for a table, as shown and described.

DESCRIPTION

FIG. 1 is a front perspective view of a table, showing a first embodiment of my new design;

FIG. 2 is a front view thereof, with the back side view being a mirror image;

FIG. 3 is a right side view thereof;

FIG. 4 is a left side view thereof;

FIG. 5 is a top view thereof;

FIG. 6 is a bottom view thereof,

FIG. 7 is a front perspective view of a table, showing a second embodiment of my new design;

FIG. 8 is a front view thereof, with the back side view being a mirror image;

FIG. 9 is a right side view thereof;

FIG. 10 is a left side view thereof;

FIG. 11 is a top view thereof;

FIG. 12 is a bottom view thereof;

FIG. 13 is a front perspective view of a table, showing a third embodiment of my new design;

FIG. 14 is a front view thereof, with the back side view being a mirror image;

FIG. 15 is a right side view thereof;

FIG. 16 is a left side view thereof;

FIG. 17 is a top view thereof; and,

FIG. 18 is a bottom view thereof.
